UNITED STATES PATENT OFFICE.

RAY J. REIGELUTH, OF NEW HAVEN, AND WILLIAM POWELL, OF HAMDEN, CONNECTICUT.

HAMMER MECHANISM USED IN DRIVING SHEATHING.

Application filed November 8, 1924. Serial No. 748,757.

To all whom it may concern:

Be it known that we, RAY J. REIGELUTH, a citizen of the United States, residing at New Haven, in the county of New Haven, State of Connecticut, and WILLIAM POWELL, a citizen of the United States, residing at Hamden, in the county of New Haven, State of Connecticut, have invented a certain new and Improved Hammer Mechanism Used in Driving Sheathing, of which the following is a specification, reference being had thereto in to the accompanying drawings.

This invention relates to a new and improved method of driving sheathing and hammer mechanism used in connection therewith.

Our invention is particularly adapted for use in connection with the driving of metal sheathing, or the like, but, of course, is not limited to such use, although so illustrated.

It is the object of this invention, among other things, to provide a simple method for so associating a hammer with a section of sheathing, or the like, that it will maintain its correct relation with the sheathing against which its blows are directed during the entire driving operation; and to provide an economical device that will function in such manner that it may be readily positioned and taken down, will hold and retain the hammer automatically in such relation to one section of sheathing that it may act thereon without the aid of the usual retaining mechanism, and which will automatically follow the section of sheathing as it is driven farther into the ground.

To these, and other ends, our invention consists in the new and improved method hereinafter described and a hammer mechanism, having certain details of construction and combination of parts, as will be hereinafter described and more particularly pointed out in the claims.

Referring to the drawings, in which like numerals of reference designate like parts in the several figures;

Figure 1 is a perspective view of a hammer having our improved mechanism attached thereto and shown in operative relation with sections of metal sheathing;

Figure 2 is a detail elevation of the hammer and our improved device connected therewith;

Figure 3 is a another elevation thereof; and

Figure 4 is a detail plan view of the hammer mechanism.

In the drawings, the reference numerals 10, 11 and 12 indicate sections of metal sheathing which have curved edges 13 whereby one section may have an interlocking engagement with another section, as shown. This sheathing has heretofore been driven into the ground by a steam hammer supported usually by a derrick or similar device and held against lateral movement by timbers or the like. Frequently these timbers, as well as the steam hammer, must be held in position by manual means. When such means are used, the operator must constantly watch the hammer while in operation to insure its proper functioning and that the blows delivered thereby are direct as distinguished from tangential or glancing blows. All the means heretofore devised for driving sheathing with a hammer or the like are also limited to such sheathing as is driven vertically and cannot be used when the sheathing is in any other position than vertical.

In our device herein shown, the hammer is held in position without the aid of timbers or supporting cables, ropes, or the like, and automatically drives a section of sheathing down to the desired depth without any further attention whatsoever from an operator.

We have shown in the drawings a conventional form of steam hammer, which consists essentially of a central cylinder 14, an upper cylinder 15, and a lower cylinder 16. Steam is admitted to the central cylinder upon one side and exhausted through the opening 17 upon the other side. Mounted within these cylinders is a steam actuated piston, not shown, which functions with the anvil plate 18.

Connected with the upper cylinder 15 is a head plate 19, through which is an eye 20 to provide convenient means for securing a hook or the like of a lifting device, whereby the steam hammer may be raised and lowered and moved about while being positioned.

Connected with the lower end of the steam hammer are lugs 21, upon the inner faces of which are wearing plates 22 having

an open space therebetween slightly wider than the thickness of a section of sheathing.

The parts above described are old and well known in the art and require no further description herein.

Our improved device consists essentially of a guide plate 23, which in cross section is curved to conform substantially with the curve of the edges of a section of sheathing 10 so that it will fit into one of such edges substantially as one section of sheathing fits in and engages the edge of the next adjoining section. Near the opposite ends of this guide plate are secured the cross heads 24 15 having openings therein, and through which project the ends of the yoke bar 25, in the manner shown, and by means of the nuts 26 are rigidly secured thereto. We have shown two of the yoke bars embracing 20 the steam hammer that cooperate to rigidly secure the guide plate thereto, but a greater number of such yoke bars and cross heads may be used if desired.

In operation, the hammer is placed in 25 position substantially as shown in Figure 1, that is with the two sheathing sections 12 projecting upwardly between the plates 22 and the underside of the anvil plate 18 resting upon the top thereof with the guide 30 plate 23 having an intermeshing engagement with the adjacent sheathing section 11. By this means the hammer is held in correct alignment with the sheathing, the guide plate 23 preventing tilting thereof, 35 and a positive, direct blow is delivered on the center line of the interlocking edges 13 at the upper-end of the sheathing sections. The hammer, by its weight, always maintains its position on the top of the sheathing 40 sections and therefore follows the sections downwardly as they are driven into the ground. The sections of sheathing are driven by this method and mechanism by the engagement of the guide with the curved 45 edges of the adjacent section which maintains the hammer in alignment not only with the sections being driven but with the adjacent sections. These operations are continued until all the sections have been 50 driven.

Obviously, as the hammer is aligned and held by the sheathing, and if the same is driven on an angle to the vertical, it will

operate on this same angle and deliver direct blows upon the end of the sheathing 55 without the aid or assistance of other mechanisms.

There are minor changes and alterations that may be made within our invention, aside from those herein suggested, and we 60 would therefore have it understood that we do not limit ourselves to the exact construction herein shown and described, but claim all that falls fairly within the spirit and scope of the appended claims. 65

Having described our invention, what we claim as new and desire to secure by Letters Patent, is:—

1. A hammer for driving sheathing, and means thereon for guiding its movement by 70 engagement solely with adjacent sheathing.

2. In mechanism for associating a hammer in operative relation to sheathing; a cross head; means for attaching the cross head to the hammer; and a guide plate connected with the cross head. 75

3. In mechanism for associating a hammer in operative relation with sheathing; a plurality of cross heads arranged in the same plane; means for separably securing 80 the cross heads to the hammer; and a guide plate connected with the cross heads.

4. In mechanism for associating a hammer in operative relation with sheathing; a plurality of cross heads arranged in the 85 same plane; means for separably securing the cross heads to the hammer; and a curved guide plate connected with the cross heads.

5. In mechanism of the character described, one or more cross heads connected 90 with a hammer; a yoke bar connected with each of the cross heads, whereby the same are rigidly secured to the hammer; and a guide plate connected with the cross heads.

6. In combination with sheathing having 95 grooved edges and a hammer for driving the sheathing; a guide plate connected with the hammer that has an intermeshing engagement with a grooved edge of the sheathing; and means for securing the guide plate 100 to the hammer.

In testimony whereof, we have hereunto affixed our signatures.

RAY J. REIGELUTH.
WILLIAM POWELL.
